AUTOMATIC PHONOGRAPH

Richard S. Cranner, Philadelphia, Pa., assignor to
 Philco Radio and Television Corporation,
 Philadelphia, Pa., a corporation of Delaware

Application May 15, 1941, Serial No. 393,636

11 Claims. (Cl. 274—10)

This invention relates to automatic phonographs of the type wherein the record-changing cycle is initiated by a trip mechanism responsive to the rate of movement of the tone pickup over the record being reproduced.

More particularly, the invention relates to that type of trip which is adapted to function at the end of a recording, as the pickup stylus moves out of the reproducing grooves into a spiral of greater pitch, or an eccentric groove; or in the event that the tone-arm moves too rapidly at any time during the playing of a recording. By way of example, the trip itself may be of the type which is triggered by the more rapid than normal movement of the pickup and which, in turn, serves to trigger a suitable mechanism adapted to lift the pickup and swing it off the record, in order that a succeeding recording may be placed upon the turntable.

Many of the trip mechanisms of this general character, which has been employed heretofore, have been of a more or less complicated nature, embodying a large number of moving parts. The use of many parts not only raises the manufacturing cost of the trip mechanism, but has an additional disadvantage in that the trip mechanism, normally in operation, requires considerable energy for its actuation. This energy must come from the movement of the tone-arm, which movement is, in turn, brought about by the co-operation between the stylus and the record groove. Thus, it can be seen, especially with the very light stylus pressures now in use, that there may be a tendency toward bad tracking, that is, the needle point will often ride up one side of the groove and thereby distort the recorded signal.

The principal object of the present invention is to overcome the aforesaid difficulties by the provision of a trip mechanism which is simple to manufacture, embodies relatively few moving parts, and which requires very little energy to operate its trip restraining means.

A further object of the invention resides in the provision of a member moving in a predetermined relation to the movement of the tone-arm; which member carries with it a novel switch, the contacts of which remain open during normal movement of the pickup, and close when said pickup moves more rapidly across the record.

The invention also has for an object the provision of a velocity responsive trip mechanism embodying a switch, wherein the closing of the switch contacts completes an electrical circuit to an electrically-operated device, which is adapted

to initiate operation of the tone-arm lifting mechanism.

The invention may be fully understood by reference to the following description taken together with the accompanying drawings.

In the drawings,

Fig. 1 is a perspective view of a phonograph pickup assembly embodying the invention;

Fig. 2 is a perspective view taken from a different angle, particularly illustrating the tone-arm lifting device, with certain parts broken away for the sake of illustration;

Fig. 3 is a detail sectional view of the switch mechanism; and

Fig. 4 is a diagrammatic illustration of the switch-controlled circuit.

Referring more particularly to the drawings, in Fig. 1 is illustrated an automatic phonograph comprising the usual turntable 1, on which is carried one or more sound records 2, fitted over a central spindle 3. The turntable is driven by suitable means (not shown) preferably taking the form of an electric motor and such transmission elements as may be desirable. A tone-arm 4 is swingingly mounted in cooperative relation with the turntable, as by means of the pivot support generally indicated by the reference character 5. Freedom for raising and lowering movements of the tone-arm is provided by a further pivot 5a (see Fig. 2). Thus, as is customary, the tone-arm is adapted to move laterally over the record and may also be raised or lowered with respect thereto. A base plate 6 provides common support for both the turntable and the tone-arm.

Tone-arm 4 is equipped with a suitable pickup, or reproducer, which includes a stylus 7. This pickup is adapted to translate the undulations of the record grooves into corresponding electrical currents which are supplied to an amplifier and thence to a loudspeaker, as is well understood.

Referring to Fig. 2, it will be seen that up and down movements of the tone-arm 4, are accomplished by means of a raising and lowering bell crank 8 pivotally attached to a member 9, as at 10. Member 9, in turn, is pivoted to the rotatable support 5 by a pin indicated at 11. One arm of the bell crank 8 has a downwardly extending actuating portion 12, while the other arm 14 is pinned to an upwardly extending lift member 15 by means of a pivot 16. The lift member 15 carries at its upper end a rod 17 adapted to engage the tone-arm. The lift assembly, comprising member 15 and rod 17 extends through an opening 18 in the supporting base plate 6, to permit

horizontal swinging of the lift mechanism as the support 5 rotates, in response to movement of the tone-arm across the record.

The lifting mechanism is actuated by means of a pivoted arm 19 whose operation will be described later. For the present, it is sufficient to state that when the depending portion 13 of bell crank 8 is moved by arm 19 to the right, as viewed in Fig. 2, the lift member 15 is raised, bringing the upper end of rod 17 into engagement with the tone-arm. Continued upward movement of the lift-arm 15 causes the tone-arm 4 to be lifted off the record 2. In the meantime, however, the weight of the tone-arm acts to rotate the entire lifting mechanism about the main pivot 11, thereby to initiate operation of a means for moving the raised tone-arm so as to condition it for repeated playing of the record or the playing of a succeeding record. The present invention is not directly concerned with this latter means and for the present purpose a brief description thereof will suffice. The member 9 has an extending arm 20 on the end of which there is provided a cam follower 21 which is adapted to seat in an eccentric cam groove provided in the upper face of a disk 22 which is geared to the turntable shaft by means of the gear 23 on the disk, gear 24 on the turntable shaft, and an intermediate gear 25. The cam groove acting through arm 20 serves to rotate the tone-arm support 5, thereby rotating the tone-arm about its vertical pivot. Since this mechanism for rotating the tone-arm through an arc when it is in raised position is well known, and since the present invention is not directly concerned with it, it is unnecessary to illustrate or describe the said mechanism in further detail. Hence, it has been deemed unnecessary to illustrate the cam groove in the upper surface of disk 22.

The present invention is concerned, however, with an additional function of the rotating disk 22 which results from spaced projections 26 on the underside of the peripheral portion of the disk. The purpose of these projections will be described later.

Referring again to Fig. 1, it will be seen that the arm 19 is shaped as illustrated and is pivoted at 27 to a supporting bracket (not shown) carried by the supporting table 6. The free end of arm 19 is curved as illustrated, and is adapted to engage and actuate the tone-arm lifting device as described above with reference to Fig. 2. The arm 19, in turn, is adapted to be actuated by a cam 29 carried by the rotating disk 22. The cam actuation of arm 19 is effected by means of a pivoted cam follower 30 on the said arm. The arm 19 has turned-up lugs 31 and 32 which serve as stops for the element 30 which is normally maintained against stop 32 by means of spring 33 secured at one end to a lug 34 on element 30 and at its other end to a lug 35 on arm 19. The arm 19 is urged toward operative engagement with cam 29 by a spring 36 secured at one end to the lug 35 and at its opposite end to a lug 37 which may be fixed to the frame of the machine. Normally, however, the arm 19 is latched in inoperative position against the action of spring 36 by a latch member 38 which is pivoted at 39 to a supporting bracket 28. The latch member has a hook-like end which engages a small knob 40 on arm 19. The latch member 38 is urged to latching position by spring 41, one end of which is anchored to the stationary support or

5 bracket 28. When the arm 19 is latched in inoperative position as shown in Fig. 1, the element 30 is out of the path of cam 29, and, therefore, the cam is free to rotate without actuating arm 19.

Latch member 38 is adapted to be actuated by the novel trip means now to be described, which is responsive to the rate of movement of the tone-arm over a record.

10 At the lower end of tone-arm support column 5 is fixed an arm 42, constrained to move with tone-arm 4 and generally underlying the same. The outer end of arm 42 is forked as at 43-43 and extends over an arcuate plate 44, which may be fixed to the frame of the machine, as at 45. A second arcuate plate 46 overlies the forked end of arm 42, and is carried by an arm 47 which is centrally pivoted as at 48, to the machine framing 28. The opposite end of arm 20 47 is provided with a roller 49, adapted to ride over the lower peripheral surface of disk 22 and be actuated by the spaced projections 26 thereon.

As appears most clearly in Fig. 3, the assembly embraced between forks 43-43 includes a block 50, which moves between the arcuate plates 44 and 46, as the tone-arm moves across the record. At such times as roller 49 is in contact with the plane face of disk 22, plate 46 will bear firmly against the upper edge of block 50, thus holding it against movement between the two arcuate plates. However, when one of the projections 26 strikes the roller 49, arm 47 is rotated slightly about its pivot 48, thereby moving upper plate 46 out of engagement with block 50. Thus, at regular intervals, determined by the speed of rotation of disk 22 and the spacing of projections 26 thereon, plate 46 is pulsed upwardly and permits block 50, under the influence of spring 51, to "inch" forward in the direction of rotation followed by arm 42. A spring may be provided as at 52, to insure firm contact between the pulsing plate 46 and the cooperating block 50, when roller 49 is not in contact with one of the projections 26.

45 With especial reference to Fig. 3, it will be seen that a switch box, generally designated by the reference character 53, is mounted between the forked ends 43-43 of arm 42. This box comprises relatively movable parts, one of which is rigidly connected to one of the arms 43 as by means of lug 54, while the other part is carried by the block 50. Block 50, in turn, is slidably mounted on a short shaft 55 which is fixed to the opposite fork arm. Electrical contact prongs 56 and 57 are carried by the respective parts of the switch box, and the spring 51 is interposed between the two sections. It will be obvious that suitable insulation should be provided between the contact prongs and the 60 associated box structure, or the box itself may be made of insulating material.

The switch contacts 56 and 57 serve to control a solenoid or electromagnetic device 58 whose armature 59 is connected to latch member 38. 65 The contact prongs are connected in circuit with the solenoid as illustrated in Fig. 4. Any suitable source of energizing current may be utilized, for example, the solenoid may be energized from the same source as is utilized to operate the driving motor for the phonograph. When the contact prongs are engaged, as described hereinafter, the solenoid is energized and it trips the latch member 38.

Considering the operation of the trip mechanism including the above-described switch, as

the tone-arm moves over the record, the arm 42 moves correspondingly. During the intervals between the successive actuations of plate 46 through the medium of projections 28, the block 50 is frictionally held by plates 44 and 46, and the movement of fork arms 43 toward the right, as viewed in Fig. 3, compresses spring 51 and brings contact prongs 58 closer to prongs 57. When plate 46 is raised by one of the projections 28, block 50 is freed and is moved by spring 51, carrying prongs 57 further away from prongs 58 and re-establishing the normal distance between the prongs.

The above-described parts of the tripping mechanism are so constructed that the latch 38 is not tripped as long as the tone-arm moves over the record at its normal rate of speed while the stylus is traversing the sound grooves of the record. During such normal movement of the tone-arm, the slight movement of the switch contacts toward each other, is insufficient to bring them into contact. Each time arcuate plate 46 is pulsed, as above described, the block 50 "inches" forward, under the influence of spring 51, thus maintaining the contacts separated. Since the intervals at which the plate 46 is pulsed, are fixed by the spacing of projections 28, and the speed of rotation of disk 22 driven from the constant speed turntable driving means, the operation of latch tripping solenoid 58 is dependent entirely upon the rate of movement of the tone-arm as it traverses a record.

As set forth above, the purpose of the tripping device is to operate the tone-arm lifting and swinging mechanism at the end of a record, and also to interrupt the playing of a record by lifting the tone-arm in the event that the tone-arm moves too rapidly at any time. The operation of the tripping mechanism at the end of a record is brought about when the stylus 7 engages a groove of steeper pitch, which causes rapid inward movement of the tone-arm. At such time, or in the event that the tone-arm should move laterally too rapidly at any time; arm 42, and hence that part of the switch box which is fixed thereto, is moved sufficiently between successive disengagements of plate 46, to permit the contacts 58 and 57 to engage one another. This trips the latch member 38, as described above, and thereby permits arm 19 to move to operative position under the influence of spring 36. This brings the curved edge 60 of cam follower 30 into the path of a shoulder 61 on cam 29. Cam follower 30 is thereby caused to move away from stop 32 into engagement with stop 31. Since the element 30 can move no further, the cam 29 causes pivotal movement of arm 19, bringing the curved end thereof into engagement with arm 13 of the tone-arm lifting device, as shown in Fig. 2. The cam 29 maintains the arm 19 in its effective position during the movement of the tone-arm to the beginning of a record by means of the arm 20, as above described. After the tone-arm has been thus moved, the cam 29 releases element 30, permitting it to move back against stop 32. The arm 19 is thereby permitted to move back to its latched position, out of engagement with the tone-arm lifting device. Consequently, the parts of the lifting device are restored by the weight of the tone-arm and by gravity acting on their own mass, to the position shown in Fig. 2, the stylus being deposited at the beginning of a record.

It will be seen that the invention provides a trip mechanism for automatic phonographs re-

sponsive to the rate of movement of the pick-up, which is of such a nature as to be very smooth and positive in its action, and which requires very little energy from the tone-arm for its operation. The trip is, in addition, relatively simple to manufacture as it requires very few moving parts.

It will be understood, of course, that the invention is not limited to the specific construction illustrated, but is capable of modification within the scope of the appended claims.

I claim:

1. In an automatic phonograph having a turntable and a tone-arm adapted to move across a recording, a trip mechanism comprising a member adapted to move with the tone-arm, a pair of electrical contacts carried by said member, means urging said contacts toward the open position, holding means preventing movement of one of said contacts thereby causing one of said contacts to approach the other as said tone-arm traverses the recording, and means operable by the turntable periodically to release said holding means at intervals bearing a predetermined timed relation to the normal speed of advance of said tone-arm.

2. In an automatic phonograph having a tone-arm, a trip mechanism comprising a member adapted to move with the tone-arm, a second member adapted to move both with the first member and with respect thereto, a cyclically-operated pulsing member adapted to engage and release said second member at intervals bearing a timed relation to the speed of advance of the tone-arm, whereby said two members periodically move with one another and with respect to each other, and trip control means operable by the relative movement of said members.

3. A construction in accordance with claim 2, wherein the phonograph turntable includes a plurality of cam projections, and wherein the pulsing member comprises a pivoted plate having a cam follower adapted to be struck and moved by the cam projections.

4. In an automatic phonograph having a tone-arm, a trip mechanism comprising a member adapted to move with the tone-arm, a second member adjacent said first member and adapted to move intermittently in the same direction as said first member, means urging said members apart, a cyclically-operating member adapted to engage and release said second member at timed intervals, whereby said two members periodically move with respect to each other, and trip control means operable by the relative movement of said members.

5. In an automatic phonograph having a tone-arm adapted to move over a recording, a trip mechanism operable by said tone-arm, said trip mechanism comprising a first member driven by said tone-arm continuously in one direction, a second member adjacent said first member and adapted to move intermittently in the same direction as said first member, means urging said members apart, means for periodically restraining said second member against movement, whereby said two members periodically move toward and away from each other, and trip control means operable by the relative movement of said members.

6. In an automatic phonograph, a turntable supporting a sound record, a tone-arm carrying a stylus adapted to engage the record grooves, means for lifting said tone-arm to remove said stylus from the record, a pivoted member oper-

able by said turntable for actuating the lifting means, means urging said pivoted member toward operative relation with said turntable, means for latching said member in inoperative position, and means responsive to the rate of movement of said tone-arm for tripping said latching means when the tone-arm moves in excess of a predetermined rate, said tripping means including an electromagnetic latch-releasing device, a member movable with the tone-arm, a pair of electrical contacts carried by said member and adapted to energize said latch-releasing device when said contacts are closed, means urging said contacts toward the open position, holding means adapted to prevent movement of one of said contacts with said member thereby causing one of said contacts to approach the other, means operable by the turntable periodically to release said holding means at intervals bearing such a predetermined timed relation to the normal speed of advance of said tone-arm as to insure that said contacts will remain open during advance of the tone-arm at a normal playing rate, and that said contacts will close upon advance of the tone-arm at a greater-than-normal rate.

7. In an automatic phonograph of the type having mechanism for raising a tone-arm and swinging it off of the record and a latch for normally holding said mechanism inoperative, a latch-tripping mechanism responsive to the rate of movement of said tone-arm, comprising an electromagnetic device adapted to release the latch, a member movable with the tone-arm, a pair of elements carried by said member and carrying electrical contacts, the contacts being adapted to energize said electromagnetic device when in the closed position, spring means urging said elements away from each other, frictional means adapted to hold one of said elements against movement with said movable member, thereby causing one of said contacts to approach the other, and means operative periodically to release said frictional means at intervals bearing such a predetermined timed relation to the normal speed of advance of said tone-arm, that under such normal speed conditions said elements are moved apart under the influence of the spring means before the contacts have closed.

8. In an automatic phonograph having a turntable and a tone-arm, a trip mechanism comprising a pair of electrical contacts adapted to move with the tone-arm, resilient means urging said contacts toward the open position, a pair of plates adapted to restrain one of said contacts,

thereby preventing movement of said contact with the tone-arm and causing the other contact to approach the restrained contact against the action of said resilient means, and means for periodically releasing the restraint of said plates at intervals bearing a predetermined timed relation to the normal speed of advance of said tone-arm.

9. In an automatic phonograph having a tone-arm adapted to move across a recording and means for lifting the tone-arm from the recording, a trip mechanism for controlling said lifting means, comprising a switch having relatively movable contact members, means operable by said tone-arm for moving one of said members continuously toward another of said members during the movement of the tone-arm across the recording, means for moving said other member intermittently away from said one member at predetermined periods of substantially equally-spaced time relation, and means operable by the engagement of said members for initiating operation of said lifting means, whereby said lifting means is actuated only in the event that the tone-arm moves at a rate sufficiently great to enable said one member to overtake and engage said other member.

10. In an automatic phonograph having a turntable and a tone-arm, a trip mechanism comprising an electrical contact member, a second electrical contact member, means tending to move the second contact toward the first contact when the tone-arm moves across the turntable, means tending to move said first contact away from said second contact, and means for alternately and periodically restraining and releasing said first contact against the action of the means tending to move it away from said second contact, whereby the distance between said two contacts will be alternately diminished and increased.

11. In an automatic phonograph having a turntable and a tone-arm, a trip mechanism comprising an electrical contact member, a second electrical contact member, means tending to move the second contact toward the first contact when the tone-arm moves across the turntable, resilient means tending to move said first contact away from said second contact, and means for alternately and periodically restraining and releasing said first contact against the action of the resilient means, whereby the distance between said two contacts will be alternately diminished and increased.

RICHARD S. CRANMER.
